UNITED STATES PATENT OFFICE.

JENNINGS SCOTT McCOMBE, OF DOBBS FERRY, NEW YORK.

SUPPORT FOR LEAVES OF LOOSE-LEAF BINDERS.

947,977.

Specification of Letters Patent.

Patented Feb. 1, 1910.

Application filed September 11, 1908. Serial No. 452,568.

To all whom it may concern:

Be it known that I, JENNINGS SCOTT McCOMBE, a citizen of the United States, and a resident of Dobbs Ferry, in the county of 5 Westchester and State of New York, have invented certain new and useful Improvements in Supports for Leaves of Loose-Leaf Binders, of which the following is a specification, taken in connection with the 10 accompanying drawing, which forms a part of the same.

This invention relates to loose leaf binders and more particularly to supports for the leaves of a loose leaf binder, which supports 15 may be incorporated in the binder forming a part of the extensible pillars or posts. By incorporating one, or a plurality, of my supports in the posts or pillars of the binder, I support the different leaves or papers at 20 points intermediate of the cover and back, and permit the ready insertion of new matter or the withdrawal of old matter from the binder by simply disconnecting two sections of the pillar or post at the desired 25 point. The removed pages of the binder are temporarily supported by my supports without the necessity of threading them off and on the posts or pillars of the binder. In the preferred construction of my invention, 30 a portion of my support is arranged as a flexible member and bends or yields readily in one direction.

In the accompanying drawing showing 35 illustrative embodiments of this invention and in which the same reference numerals refer to similar parts in the several figures, Figure 1 is a plan view of a loose leaf binder equipped with my invention, a portion of the figure being broken away to better illustrate the support. Fig. 2 is a longitudinal vertical section on the line 2—2 looking in the direction of the arrows. Fig. 3 is a side elevation on a reduced scale of one 40 of my supports. Fig. 4 is a plan view of the head of my support taken on the line 4—4 of Fig. 3 looking in the direction of the arrow. Fig. 5 is a transverse horizontal section on the line 5—5 of Fig. 3. Fig. 6 is a side elevation similar to Fig. 3, showing 45 a modified form of support.

In the illustrative embodiments of this invention shown in the drawing 1 is a loose leaf binder having a cover 2, a back 3 and an extensible pillar or post 4. On this pillar 50 or post I mount, in any suitable manner, one

or more of my supports 5, which in the preferred construction consist of a substantially rigid body portion 6 having a rearwardly extending handle 7, and a forwardly extending blade 8. These members may be given 60 various shapes, but I preferably, though not necessarily, form them in the shape of a spear-head or pear. As shown in Fig. 1 the point 9 of the blade 8 extends approximately to the end of the contained leaves 10, 65 10, though the end 9 may extend only half the length of the sheet or at any shorter distance that may be desired. I preferably however, make the supports as shown so as to form the maximum supporting surface for 70 those leaves 10, 10 which are immediately above one of the supports 5.

In the preferred construction the blade 8 is secured in any suitable manner to the body portion 6, either being formed integral with 75 it as shown in Fig. 6, or pivoted to it as shown in Fig. 1 wherein the body portion 6 is shown provided with upwardly bent portions 11 and the blade 8 with corresponding downwardly bent portions to coöperate with 80 the pivot pin 12. To permit the blade to support the leaves 10, 10 when the post 4 is disconnected for the insertion of new or the removal of old matter, I provide any suitable stop mechanism which will permit the 85 blade 8 to swing upon the pivot pin 12 in one direction, but which will limit its movement in the opposite direction. Various forms of such stop devices may be used, but for purposes of illustration I have shown a plate 90 13 secured at one end to the rigid body portion 6 by any suitable means such as by rivets 14, 14, the other end 15 of the plate 13 extending out beyond the pivot pin 12. By this construction the blade 8 is permitted to 95 swing upwardly and to conform generally to the movement of the leaves in opening and manipulating the binder, but is prevented from moving downwardly by the end 15 of the stop or plate 13. It is to be understood 100 that any other stop mechanism may be used without departing from my invention.

The rigid body portion 6 is provided with a head 16 and stem 17 to coöperate with another similar head or stem of a coöperating 105 support or with a coöperating unit 18 of the post 4. It is immaterial how the different units 18 are connected to the head 16 and stem 17, or the means employed to connect two of the supports 5 together. For pur- 110

poses of illustration I have shown the head 16 formed with a seat 19 and radial slots 20, 20 for the reception of the stem 17; the radial slots 20, 20 coöperating with the ends of 5 the pin 21 carried by the stem 17. The parts are so arranged that by inserting the stem 17 with its pin 21 into the seat 19 the ends of the pins 21 will coöperate with the radial slots 20, 20 until the end of the stem 17 10 reaches the limit of its movement in the seat 19, when the two members may be given a partial rotation, the ends of the pins 21 being thereby brought into a groove 22 locking the parts together.

15 Various other means of connecting and disconnecting the supports and units or sections to the post 4 may be employed, the one shown being merely for purpose of illustration.

20 In some cases it may be advantageous to have the support formed of one piece, the blade 8 being formed integral with the rigid body portion 6. Such a construction is shown in Fig. 6 where the blade 23 is shown 25 formed integral with the body portion 24. This blade 23 may under some circumstances be formed of stiff rigid material preventing it being bent to any appreciable extent, while for other uses it may be formed of 30 spring metal, or other similar substance, which will permit it bending more or less with the leaves of the binder.

The handle 7 of the different supports may be given various contours and may be 35 used also as an index either with or without the usual front index not shown. Numerals or letters may be placed upon them as shown in Fig. 1, where a letter A is used which may correspond with a similar letter upon the 40 front index of the binder (if one be used). These handles 7 are preferably comparatively short so as to be unobtrusive and not interfere with the filing away of the binder.

While I have illustrated in the drawing a 45 loose leaf binder with a single pillar or post,

it is to be understood that my invention is not to be limited to such binders.

Having thus described this invention in connection with the several illustrative embodiments thereof to the details of which I 50 do not desire to be limited, what is claimed as new and what it is desired to secure by Letters Patent is set forth in the appended claims.

I claim—

1. A support to support the leaves in a loose leaf binder having a body portion, interlocking members carried by the body portion adapted to interlock with other complementary members to form a pillar for the 60 loose leaf binder, and a member pivotally secured to the body portion, the body portion and the pivoted member being formed substantially in the shape of a pear or spear-head.

2. A support to support the leaves in a loose leaf binder having a body portion, interlocking members carried by the body portion adapted to interlock with other complementary members to form a pillar for the 70 loose leaf binder, a member pivotally secured to the body portion, a handle on the body portion and a stop to limit the movement of the pivoted member carried by the body portion.

3. A support for a loose leaf binder comprising a body portion having interlocking members to coöperate with other complementary interlocking members to form a pillar or post, a handle extending to the rear of 80 the body portion, a pivoted blade mounted on the front of the body portion, and a plate secured to the body portion and having its free end extending into the path of the pivoted blade to limit its movement in one direction.

JENNINGS SCOTT McCOMB.
